Primary Examiner — Cathron C Brooks*Assistant Examiner* — W. A. Teddy Falloway(74) *Attorney, Agent, or Firm* — Medley, Behrens & Lewis, LLC; Lorri W. Cooper(57) **CLAIM**

The ornamental design for a cracker and spread container, as shown and described.

DESCRIPTION

FIG. 1 is a top perspective view of a cracker and spread container;

FIG. 2 is a bottom perspective view thereof;

FIG. 3 is a top view thereof;

FIG. 4 is a bottom view thereof;

FIG. 5 is a right side view thereof;

FIG. 6 is a left side view thereof;

FIG. 7 is a front view thereof; and,

FIG. 8 is a rear view thereof.

The broken lines shown in FIGS. 1-8 illustrate portions of the cracker and spread container that form no part of the claimed design.

1 Claim, 4 Drawing Sheets(56)
